CONVERTIBLE LADDER

Alfred A. Thompson, Dayton, Ohio

Application August 3, 1943, Serial No. 497,189

2 Claims. (Cl. 228—25)

This invention relates to convertible ladders, and its general object is to provide a ladder that can be converted from a stepladder into an extension ladder in an easy and expeditious manner, in that it includes a main section and an auxiliary section, the latter being pivotally and removably connected to the main section for use therewith as a stepladder, and when removed from the main section, can be secured to the upper portion thereof for cooperation therewith for use as an extension ladder.

A further object is to provide a convertible ladder in which the sections are rigidly associated when the ladder is used as either a stepladder or an extension ladder.

Another object is to provide a convertible ladder that is simple in construction, inexpensive to manufacture, and extremely efficient in operation, use and service.

This invention also consists in certain other features of construction and in the combination and arrangement of the several parts, to be hereinafter fully described, illustrated in the accompanying drawing and specifically pointed out in the appended claims.

In describing the invention in detail, reference will be had to the accompanying drawing wherein like characters denote like or corresponding parts throughout the several views, and in which:

Figure 1 is a perspective view of my ladder, with the sections associated for use as a step-ladder.

Figure 2 is a front view of Figure 1.

Figure 3 is an edge view of my ladder with the sections associated for use as an extension ladder.

Figure 4 is a front view of Figure 3.

Figure 5 is a bottom plan view of the upper step or platform of the main section.

Figure 6 is an edge view thereof.

Referring to the drawing in detail, the main section is indicated by the letter A and the auxiliary section by B. The main section includes a pair of side rails 1 having steps 2 secured to and bridging the same at regular intervals, and the rails are slightly inclined toward each other from the lower to the upper ends thereof, for disposal in converging relation. Suitable brackets may be provided for supporting the steps 2, as will be apparent.

The top step or platform 3 is wider and longer than the steps 2, and is provided with recesses 4 extending inwardly from the ends thereof, the recesses being square cornered and are disposed adjacent the front edge of the platform, as best

shown in Figure 1. Mounted in the recesses are the upper ends of the side rails 1, the recesses being of a width for the side rails to fit the same, and of a depth for the side rails to extend a considerable distance from the outer ends of the recesses to provide spaces 5, for a purpose which will be later apparent. The side walls of the recesses are beveled or slightly inclined toward the front edge of the platform, for disposal of the side rails at a forward inclination.

Secured to the under face of the platform 3 is a pair of brackets, one at each end thereof, and each bracket includes a depending plate member 6 having its forward edge curved rearwardly from the upper end thereof. Formed on and extending outwardly and at right angles from the upper edges of each of the depending plate members 6 is a pair of ears 7. The ears of the plate members receive the bolts of bolt and nut connections 8 therethrough for securing the brackets to the platform, with the ears disposed upon opposite sides of the recesses and flush with the side walls thereof, as well as flush with the outer ends of the platform and the front and rear edges of the latter as best shown in Figure 6.

The depending plate members have the upper ends of the side rails 1 fixed thereto by any suitable means such as bolt and nut connections, rivets or the like, and disposed adjacent to the rear ends of each plate member is a hole 9, the holes being disposed in registration with each other, and fixed to each of the side rails 1 is a square cornered loop member 10, the loops being disposed slightly below the uppermost step 2, as best shown in Figure 1, so as to be spaced a considerable distance below the platform.

The auxiliary section B likewise includes a pair of side rails 11 with steps 12 secured to and bridging the same at regular intervals, and the lowermost step 12 is arranged a considerable distance above the lower ends of the side rails 11, in order to provide ample overlapping space of the side rails 1 and 11, when the auxiliary section is telescopically mounted on the main section for use of the ladder as an extension ladder, as shown in Figures 3 and 4. The side rails 11 likewise converge toward each other from the lower to the upper ends thereof. In fact, the auxiliary section is exactly the same width as that of the main section throughout the height thereof and is pivotally secured to the depending plate members 6 when the ladder is used as a stepladder by a headed rod 13 that extends through the upper ends of the side rails 11 and the holes 9, and the rod is provided with a wing nut to facilitate at-

taching and removing the auxiliary section with respect to the main section, when it is desired to convert the ladder into an extension ladder.

Such conversion is brought about by removing the section B from the rod 13, and the lower portion of the side rails 11 are then applied to the upper portions of the outer faces of the side rails 1. The side rails 11 are passed through the spaces 5 of the recesses and through the loops 10 to be seated therein, the loops acting to prevent rearward and forward movement of the auxiliary section relative to the main section, and the recesses allow the side rails 11 to bear against the outer faces of the side rails 1, while the lowermost step 12 rests upon the platform, with the result it will be seen that the auxiliary section is held rigidly supported relative to the main section, when the ladder is converted into an extension ladder, as will be apparent upon inspection of Figures 3 and 4.

Suitable means is provided to limit rearward movement of the auxiliary section relative to the main section, when the ladder is used as a step-ladder as shown in Figures 1 and 2, and the means shown, include chains 14 having one of their ends connected to the side rails 1, and hooks 15 are connected to the opposite ends of the chains to be received in eyelets 16 secured to the side rails 10.

It is thought from the foregoing description that the advantages and novel features of the invention will be readily apparent.

It is to be understood that changes may be made in the construction and in the combination and arrangement of the several parts, provided that such changes fall within the scope of the appended claims.

What I claim is:

1. A ladder convertible to provide a stepladder or an extension ladder, and comprising a main section and an auxiliary section, each section including side rails having steps secured to and bridging the same, a platform secured to the up-

per ends of the main section side rails and having recesses in the ends between the front and rear edges thereof, means for removably and pivotally securing the upper ends of the auxiliary section side rails relative to the platform for use of the ladder as a stepladder, the lower ends of the side rails of the auxiliary section being receivable in the recesses in the platform when used as an extension ladder, looped members secured to the main section side rails to receive the auxiliary section side rails for securing the same to the main section side rails in cooperation with the recesses when the ladder is used as an extension ladder, and each section having its side rails converging toward each other from the lower to the upper ends thereof for the lower portions of the auxiliary side rails to fit the outer faces of the upper portions of the main side rails and the edge walls of the recesses being similarly formed at an angle.

2. A ladder convertible to provide a stepladder or an extension ladder, and comprising a main section and an auxiliary section, each section including side rails having steps secured thereto and bridging the same, a platform provided with recesses in the ends between the front and rear edges thereof, brackets fixed to and depending from the platform and having the upper ends of the main section side rails fixed thereto, means for removably and pivotally securing the upper ends of the auxiliary section side rails to the brackets for use of the ladder as a stepladder the bottom step of the auxiliary section resting on the platform, and the portions of the side rails below said step being receivable in the recesses when used as an extension ladder, and looped members secured to the main section side rails to receive the auxiliary section side rails for cooperation with the recesses in securing the same to the main section side rails when the ladder is used as an extension ladder.

ALFRED A. THOMPSON.
